UNITED STATES PATENT OFFICE

HAROLD MANSON-OLIN, OF NEW YORK, N. Y.

MINIATURE PARACHUTE.

1,108,596.

Specification of Letters Patent. Patented Aug. 25, 1914.

Application filed October 9, 1913. Serial No. 734,235.

To all whom it may concern:

Be it known that I, HAROLD MANSON-OLIN, a subject of the King of Sweden, and a resident of the city of New York, borough 5 of Brooklyn, county of Kings, and State of New York, have invented a new and Improved Miniature Parachute, of which the following is a full, clear, and exact description.

10 This invention relates to improvements in toys, and particularly to miniature parachutes, and has for an object to provide a device of this character with a guiding tube in which a loosely mounted weight is positioned so as to guide the parachute in its 15 upward travel, and also in its downward travel.

20 A further object of the invention is to provide a miniature parachute with a collapsible canopy and a tubular member connected therewith and co-acting with braces connected with the periphery of the canopy so as to limit the spreading of the canopy in its downward movement.

25 In carrying out the object of the invention a canopy of any desired kind may be provided either with or without stiffening ribs, and with a plurality of bracing members connected together at a central point near 30 the bottom of a bracing and guiding tube when the device is falling. The tube is connected near its upper end with a canopy and extends downwardly to a position in contact with the lower ends of the various bracing 35 members so as to hold the same against further movement, thus regulating the extension of the canopy. A movable member is arranged in the tube, and is adapted to automatically move to the upper end of the tube 40 when the device is thrown into the air, and to automatically move to the bottom or lower end of the tube when the device is moving downward under the action of gravity. This weight may be a solid member or 45 may be made into a plurality of parts, as for instance a plurality of shot, or if preferred a liquid may be used, as for instance, quicksilver.

50 In the accompanying drawings—Figure 1 is a section through a parachute embodying the invention; Fig. 2 is a section through the parachute shown in Fig. 1, but showing the same in a collapsible or closed position; Fig. 3 is a detailed sectional view of the guiding tube with a liquid arranged therein acting as a weight.

55 Referring to the accompanying drawing, the numeral 1 indicates a canopy formed of any desired material and provided with bracing ribs 2. At the end of bracing ribs 2 60 bracing members 3 are connected which are secured together at 4 so as to engage the lower end 5 of the guiding tube 6. Guiding tube 6 is connected at 7 near the upper end 8 to canopy 1 so that when the parachute is 65 falling canopy 1 cannot be opened beyond the position shown in Fig. 1 as the knot or connection 4 of the braces 3 beneath the lower end 5 of tube 6 prevents the further opening of the canopy. Arranged in the 70 guiding tube 6 is a weight 9 which is loosely mounted in the tube, and is designed to freely slide from one end to the other. If desired, other means besides a solid weight could be used, as for instance a liquid 10 75 (Fig. 3), which will act in a similar manner to the weight 9, that is, move from one to the other under gravity or momentum as the case may be. Preferably an operating cord 11 is connected with the lower end or knotted portion 4 of braces 3 so as to properly operate the parachute.

80 In use the parachute may be used simply as a toy or may be used for signals. When it is desired to operate the parachute the 85 cord 11 is grasped and the parachute is collapsed, as shown in Fig. 2. The parachute is then swung around in a circle or back and forth as desired, after which it is thrown into the air. The swinging and throwing of 90 the parachute into the air causes the weight 9 to press against the upper end 8 of tube 6, and in a certain sense propel the parachute in the direction desired. If the parachute has reached the extreme altitude to which 95 the power applied moves the same the weight 9 first moves downwardly under the action of gravity to the position shown in Fig. 1, and as the entire device moves downwardly the canopy opens and the weight 100 guides and steadies the device so that the descent will be comparatively slow and even.

Having thus described my invention I claim as new and desire to secure by Letters Patent, the following:

105 1. In a toy of the class described, a collapsible parachute structure, a tube connected with said parachute structure, and a weight loosely positioned in said tube for directing the movement of the parachute 110 structure in both its upward and its downward travel.

2. In a toy of the class described, a collapsible canopy, a guiding tube connected with said canopy, a plurality of bracing members connected with said canopy at its periphery, said bracing members being connected together at a point adjacent the end of said tube, whereby the tube limits the upward movement of the bracing members and the periphery of the canopy when the toy is falling, and a movable weight arranged in said tube, said weight moving automatically to the top of the tube under the action of momentum when the toy is moving upwardly, and moving to the bottom of said tube under the action of gravity when the toy is moving downwardly.
3. In a toy of the class described, a parachute structure, a tube connected near its

upper end to the canopy of the parachute structure and adapted to engage the lower portion of the canopy structure when the toy is descending so as to limit the spreading of the canopy of the parachute structure, and a weight arranged in said tube, said weight comprising a liquid, said weight being adapted to act at opposite ends of said tube as the toy is moving upwardly, and as the toy is moving downwardly.

In testimony whereof I have signed my name to this specification in the presence of two subscribing witnesses.

HAROLD MANSON-OLIN.
